Des. 229,174
Patented Nov. 13, 1973

229,174

WALL PILLAR STANDARD

Charles R. Suska, Roxbury, Conn., assignor to The
Stanley Works, New Britain, Conn.

Filed Apr. 24, 1972, Ser. No. 247,231

Term of patent 14 years

Int. Cl. D25—01

U.S. Cl. D13—6

FIG. 1

FIG. 2

FIG. 3

FIG. 4

FIG. 5

FIG. 6

FIG. 1 is a front elevational view of one form of a wall pillar standard showing my design;

FIG. 2 is a side elevational view of the wall pillar standard shown in FIG. 1;

FIG. 3 is a top plan view of the wall pillar standard shown in FIG. 1;

FIG. 4 is a front elevational view of another form of a wall pillar standard showing my design;

FIG. 5 is a side elevational view of the wall pillar standard shown in FIG. 4; and

FIG. 6 is a top plan view of the wall pillar standard shown in FIG. 4.

I claim:

The ornamental design for a wall pillar standard, as shown and described.
